(57) **CLAIM**

The ornamental design for a nasal dilator, as shown and described.

DESCRIPTION

FIG. 1 is a top plan view of a first embodiment of a nasal dilator showing my new design, the bottom plan view being flat and unornamented;

FIG. 2 is a front view thereof;

FIG. 3 is a right side view, the left side view being a mirror image;

FIG. 4 is a rear view thereof;

FIG. 5 is a perspective view thereof, showing the dilator in an in use state;

FIG. 6 is a three-quarter perspective view thereof;
FIG. 7 is an exploded perspective view thereof, in order to show aspects of the individual nasal dilator components of the design that are not otherwise apparent;
FIG. 8 is a top plan view of a second embodiment of a nasal dilator showing my new design;
FIG. 9 is a front view thereof;
FIG. 10 is a right side view, the left side view being a mirror image;
FIG. 11 is a rear view thereof;
FIG. 12 is a perspective view thereof, showing the dilator in an in use state;
FIG. 13 is a three-quarter perspective view thereof;
FIG. 14 is an exploded perspective view thereof, in order to show aspects of the individual nasal dilator components of the design that are not otherwise apparent;
FIG. 15 is a top plan view of a third embodiment of a nasal dilator showing my new design;
FIG. 16 is a front view thereof;
FIG. 17 is a right side view, the left side view being a mirror image;
FIG. 18 is a rear view thereof;
FIG. 19 is a perspective view thereof, showing the dilator in an in use state;
FIG. 20 is a three-quarter perspective view thereof;
FIG. 21 is an exploded perspective view thereof, in order to show aspects of the individual nasal dilator components of the design that are not otherwise apparent;
FIG. 22 is a top plan view of a fourth embodiment of a nasal dilator showing my new design, the bottom plan view being flat and unornamented;
FIG. 23 is a front view thereof;
FIG. 24 is a right side view, the left side view being a mirror image;
FIG. 25 is a rear view thereof;
FIG. 26 is a perspective view thereof, showing the dilator in an in use state;
FIG. 27 is a three-quarter perspective view thereof; and,
FIG. 28 is an exploded perspective view thereof, in order to show aspects of the individual nasal dilator components of the design that are not otherwise apparent.
The broken line showing of human facial features are directed to environment and for illustrative purposes only; the broken lines form no part of the claimed design.
